UNITED STATES PATENT OFFICE.

WILLIAM ROOKE, OF JACKSON, MICHIGAN, ASSIGNOR TO THE MICHIGAN MANUFACTURING COMPANY, OF SAME PLACE.

TWO-WHEELED VEHICLE.

SPECIFICATION forming part of Letters Patent No. 350,158, dated October 5, 1886.

Application filed August 7, 1886. Serial No. 210,315. (No model.)

To all whom it may concern:

Be it known that I, WILLIAM ROOKE, a citizen of the United States, residing at Jackson, in the county of Jackson and State of Michigan, have invented certain new and useful Improvements in Two-Wheeled Vehicles, of which the following is a specification, reference being had therein to the accompanying drawings.

10 This invention relates to certain improvements upon two-wheeled vehicles, particularly to that class in which the seat is supported by bars loosely connected at their forward ends to the thills, and supported intermediately between their ends upon springs or a spring-bar interposed between the shafts and the seat-supporting bars, and in which the foot-rest most commonly consists of a crate-like device situated between the shafts and in front of the 20 axle; and it consists in certain new arrangements of parts, whereby the angle of the seat and its supporting-bars may be changed to suit the weight which the seat may have to carry, and also whereby the foot-rest may be 25 adjusted relatively to the seat in order to give more or less leg-room.

Figure 1 is a side elevation of a two-wheeled vehicle embodying my improvements, the near wheel being removed. Fig. 2 is a top 30 plan view of the same. Figs. 3, 4, and 5 are detail views, in perspective, of various parts enlarged.

In the drawings, A A represent the shafts, connected at their rear ends to the axle M, 35 which in turn is supported by wheels N. The seat O is supported on the rear ends of two bars, B B, loosely connected at their forward ends to the shafts A, and supported intermediately between their ends on a cross-bar, D, 40 extending between the shafts, to which it is connected by a spring, d.

In order to give the desired flexibility and permit the adjustment, to be hereinafter referred to, I prefer hinge-connections between 45 the seat-supporting bars and the cross-bar D. The form of such a connection will be better understood from an examination of Fig. 5, wherein G represents a plate carrying two perforated projecting ears, between which is 50 pivoted a plate or bar, E, attached to the under side of the seat-supporting bar, and hav-

ing its forward end, e, expanded in the form of an eye, which lies between the ears of plate G, and through which passes the pivot-bolt g.

It is quite customary in vehicles of this 55 character to adjust the position of the seat to suit the weight of the person who is to occupy it, and I have devised a novel arrangement of parts for effecting such adjustment. F is a metallic eye carried by the front 60 end of bar B, and engaging with a loop carried at the upper end of a screw-threaded rod, J, which passes through the shaft, and is confined in place by nuts K L. It will be seen, without further description, that by means of 65 the nuts K L the rod J may be adjusted to any desired vertical position and there locked in place, such adjustment causing the bar B to turn about its hinge-connection g, and thus change the position of the seat O.

C C represent the curved or angular bars which carry the slats forming the foot rest or support. These bars C are supported at their forward ends, either meditately or immediately, by the shafts, and may be connected at their 75 rear ends either to the axle or to the seat supporting bars B, as shown.

In order to change the position of the foot-rest relatively to the seat to suit the person riding, giving more or less leg-room, as may 80 be desirable, I make the forward end of the foot-rest vertically adjustable, to accomplish which the forward ends of bars C C are extended and provided with a series of apertures, e e. The bars C C are connected with 85 the cross-bar D by means of bolts h h, which pass through said apertures e, and also through perforated ears carried by plates H, attached to one of the faces of said bar D, as will be clearly seen on examination of Fig. 4.

What I claim is—

1. In a two-wheeled vehicle, the combination of the axle, the shafts, the seat-supporting bars attached to the shafts at their forward ends, a seat supported at the rear ends of said bars, a spring supplemental to said bars, situated in front of the seat, and upon which the bars are supported, and means for vertically adjusting the forward ends of said bars, substantially as set forth.

2. In a two-wheeled vehicle, the combination of the axle, the shafts, the seat-support-

ing bars, a seat supported at the rear ends of said bars, a spring, *d*, between the shafts in front of the seat, a cross-bar, *D*, interposed between the seat-supporting bars and the spring *d*, and means for vertically adjusting the forward end of the seat-supporting bars, substantially as set forth.

3. In a two-wheeled vehicle, the combination of the axle, the shafts, the seat supporting bars, the screw-rods *J*, passing through the shafts and carrying at their upper ends eyes or loops, to which the forward ends of the bars *B* are hinged, means for vertically adjusting said screw-rods, and a support for said bars in rear of their hinged front ends, substantially as set forth.

4. In a two-wheeled vehicle, the combination of the axle, the shafts, the seat, the foot-rest non-adjustably supported at its rear end, and means for adjusting the forward end of the foot-rest relatively to the seat and to its rear end, substantially as set forth.

5. In a two-wheeled vehicle, the combina-

tion of the axle, the shafts, the seat, a foot-rest having the extended bars *C C*, provided with a series of perforations, *e*, and the bolts *h*, passing through said perforations and supporting the forward end of the foot-rest, substantially as set forth.

6. In a two-wheeled vehicle, the combination of the axle, the shafts, the seat-supporting bars attached to the shafts at their forward ends, a support for said bars in rear of their forward ends, means for vertically adjusting the forward ends of the bars, a foot-rest, and means for adjusting the foot-rest relatively to the seat and independently of the adjustment of the seat-supporting bars, substantially as set forth.

In testimony whereof I affix my signature in presence of two witnesses.

WILLIAM ROOKE.
